UNITED STATES PATENT OFFICE.

WILLIAM S. THOMAS, OF ROSELLE, NEW JERSEY, ASSIGNOR TO THOMAS SPARK PLUG COMPANY, OF ROSELLE PARK, NEW JERSEY.

ELECTRODE-INSULATING MEANS FOR SPARK PLUGS.

Application filed January 4, 1922. Serial No. 526,869.

To all whom it may concern:

Be it known that I, WILLIAM S. THOMAS, a citizen of the United States, residing at Roselle, in the county of Union and State 5 of New Jersey, have invented certain new and useful Improvements in Electrode-Insulating Means for Spark Plugs, of which the following is a specification.

One object of my present invention is to 10 provide a spark plug electrode insulating structure including a mica tube so arranged and protected that it will not be affected by oils, gases or products of combustion and thus keep the mica tube in such condition that it 15 will continue during the use of the plug to provide a practically perfect electrode insulator.

Another object is to so construct and arrange my improved insulating means that 20 it can be used advantageously in connection with various forms of spark plug structures and with practical advantage in connection with the structure of my invention as covered in my co-pending application for 25 United States Patent, Serial No. 480,913.

These objects, and other advantageous ends which will be described hereinafter, I attain in the following manner, reference being had to the accompanying drawings in 30 which—

Figure 1 is an elevation of an insulated electrode including my invention,

Figure 2 is an enlarged longitudinal section of Figure 1,

Figure 3 is a section taken on the line 35 3—3 of Figure 2, and

Figures 4, 5 and 6 are detail sections showing various modifications of the insulating means.

Referring to Figures 1 to 3 of the drawings, with the exception of the construction and arrangement of the mica tube and its casing as will be more definitely described hereinafter, the structure is similar to that 40 covered in my co-pending application for United States patent above mentioned and it will be only necessary to again describe those parts which are essential to give a proper understanding of the features of my 45 present invention.

An insulating core 8 which may be made

of any suitable electrode insulating material includes a body portion 9 which is externally screw threaded at its top as shown at 10. A cap 11 has internal screw threads 12 to 55 allow the cap to be screwed on the body portion 9; said cap includes a chamber 13 positioned directly above the top of the body portion 9. This cap has radially disposed holes or perforations which communicate with the atmosphere and also with the chamber 13 allowing air to pass into and out of the chamber 13. The body portion 9 has an enlarged external shoulder or flange 15 which is positioned above its 60 lower end or nose 16. This flange 15 is usually provided on spark plug electrode insulator bodies to effect the connection of the insulator body with the metallic jacket (not illustrated) to allow the spark plug 70 to be screwed into the cylinder of an internal combustion engine. Furthermore the body portion 9 has a cylindrical cavity 17 extending axially downward from the top surface 18 of the body portion 9. This 75 cavity 17 terminates in a lower shoulder 19. A counter cavity 20, of smaller diameter than the cavity 17, leads downwardly from the shoulder 19 and forms the top of a transversely extending web 21; said web 80 being formed integral with the other part of the core body 9. A recess or cavity 22 extends upwardly and axially from the bottom surface 23 of the insulator nose 16 and the upper wall of this recess 22 provides the 85 bottom of the web 21.

An electrode wire 25 has a screw threaded portion which extends through a central hole 26 in the web 21 of the insulator; a part of said screw threaded portion of the electrode 90 wire 25 extending upwardly into the space provided by the cavity 17. Another part of this screw threaded portion of the electrode wire extends below the web 21 and upon this latter part of the screw threaded 95 portion of the electrode wire is screwed a small nut 27 which abuts the under surface of the web 21. A second nut 28 is screwed on the upper portion of the electrode wire and abuts the top surface of the web 21 so 100 that the web 21 is clamped between the nuts 27 and 28.

In accordance with my present invention I provide a mica tube 24 and enclose this mica tube in a casing 24^a of glass, porcelain or other vitreous material as clearly shown in Figures 2 and 3. The preferred manner of incasing said mica tube is to mold, coat or blow the vitreous material entirely around the mica tube so that there will be no portion of the mica exposed and the mica tube will be embedded entirely within the integral casing 24^a. This casing 24^a of vitreous material fits the cavity 17; the lower edge of said casing resting on the shoulder 19. The internal diameter of the casing 24^a is such as to allow the electrode wire 25 to extend upwardly therein so as to be spaced from the inner surface of the casing as illustrated in Figures 2 and 3.

The casing 24^a with the mica tube therein extends upwardly from the shoulder 19 which is below the flange 15 to a position above the flange 15; said position preferably being coincident or flush with the upper surface 18 of the body portion 9. The diameter of the electrode wire 25 is small compared to the diameters of the counter cavity 20, recess 22 and internal diameter of the casing 24^a so that there is a comparatively large air space present between the electrode wire and the inner surface of the casing 24^a.

As illustrated the cap 11 has a metallic head 29 secured thereto and I have illustrated the head 29 including an enlarged flange 30 which abuts the uppermost surface of the chamber 13, and an angular portion 31 which may be embedded in the material of the cap so as to prevent rotation between the head 29 and the cap 11. The head 29 includes an upwardly extending screw threaded stem 32 to which a thumb nut 33 is secured and I have also illustrated two other nuts 34 screwed on said stem and between these nuts and the thumb nut the usual electrode wire can be clamped. An electric conducting member 35 depends from the head 29 and I have illustrated this member in the form of a metallic tube which extends downwardly through the space within the casing 24^a; said tube 35 being of smaller diameter than the internal diameter of the casing 24^a so that there is an air space entirely surrounding the tube 35. The lower end of the metallic tube 35, when the cap 11 is screwed on the body portion 9, is adapted to engage over the top portion of the electrode wire 25 and make electric connection therewith. The lower end of the tube 35 is slotted so as to make the same slightly resilient and capable of yielding so as to pass over the top of the electrode wire and then move into firm fitting engagement with the electrode wire.

It will be noted that the metallic members 25 and 35 constitute an electrode which

extends through the space provided by the internal diameter of the casing 24^a and that the embedded mica tube 24 entirely surrounds the electrode. Thus the incased mica tube serves as a practically perfect insulator and guard against transverse current leakage or short-circuiting. Thus with this construction I am enabled to increase to a very high degree the possibility of maintaining the dielectric strength of the insulator and to eliminate electrical leakage through conduction at or about the shoulder or thick portion 15 of the insulator and also at portions above and below said portion 15.

By incasing the mica it is impossible to impair the insulating qualities thereof since oils, gases or products of combustion which may either pass upwardly or downwardly cannot engage the mica and hence will be kept in such condition as to advantageously serve as an insulator.

In Figure 4, I have shown a construction in which the lower edge of the mica tube and the inner and outer side surfaces are covered by a vitreous case 24^b and while this structure is capable of protecting practically all of the mica tube the same is not as desirable as that described in connection with Figures 1 to 3 inclusive, however, the same can be used in some instances.

Figure 5 shows an arrangement where the upper and lower ends as well as the inner surface of the mica tube are covered by a vitreous case 24^c and in Figure 6 I have shown a construction where the mica tube has its inner surface and lower edge covered by a vitreous case 24^d. In each instance the lower edge of the mica tube and the inner surface is protected so that the lower end of the case can rest upon the shoulder 19.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. Spark plug electrode insulating means including a mica tube entirely covered with vitreous material and spaced from the electrode; substantially as described.

2. Spark plug electrode insulating means including an insulating tube of high dielectric strength; an integral vitreous covering for the tube, said tube with its covering being spaced about the electrode, substantially as and for the purposes described.

3. Spark plug electrode insulating means including a mica tube embedded in a casing

of vitreous material and spaced about the electrode, all portions of said casing being integral; substantially as described.

4. In a spark plug; a body having a channel; an electrode extending through said channel; insulating means consisting of a mica tube surrounding the electrode but

spaced therefrom, said mica tube being provided with a vitreous protecting coating, substantially as and for the purposes described. 10

In testimony whereof I have signed my name to this specification.

WILLIAM S. THOMAS.
